PROCESS AND APPARATUS FOR FORMING
TOBACCO BUNCHESPontus Peterson, Garden City, N. Y., assignor to
International Cigar Machinery Company, a
corporation of New Jersey

Application June 20, 1946, Serial No. 678,072

18 Claims. (Cl. 131—39)

1

This invention relates to the manufacture of cigars, more particularly to an improved machine and method for making blended cigar bunches.

A number of cigar manufacturers blend their main filled tobacco, which may be Porto Rican, Pennsylvania, or other suitable filler tobacco, with Havana filler tobacco or some other suitable blending tobacco. Hitherto, the blending tobacco has been manually laid in a more or less continuous stripe on top of the stream of filler tobacco in the filler feed channel of the cross feed of a cigar machine, of the type disclosed in U. S. Patent No. 1,740,571 to Wilhelm B. Brohander in which severed lengths cut from the stream in the cross feed are assembled side by side for charge cutting. Considerable trouble in getting a uniform blend was caused by lack of uniformity in the manual feeding.

I have discovered that uncertainties can be eliminated and a substantially uniform blend obtained in a simple and efficient manner with a cigar machine of the type disclosed in Wheeler Patent No. 2,311,011, or U. S. Patent 2,470,766 to Durning, by partitioning the cross feed longitudinally and laying blend tobacco on one side of the partition and the body tobacco on the other side. By adjusting the position of the partition, exactly the desired proportion may be obtained and the amount of blending tobacco accurately measured.

In a machine of this type with a partitioned cross feed, charges cut from the forward end of the cross feed are assembled one on top of the other so that a column is formed which in horizontal cross section contains a substantially uniform proportion of blend and body tobacco at any position along its height. Charges cut from this column will, therefore, produce a uniformly blended bunch. This charge has the further advantage that the blend may be located at any desired position with respect to the remainder of the charge and with respect to the completed bunch.

One of the main objects of this invention is to provide a cigar machine wherein properly blended cigar bunches will be obtained from filler tobacco blended in the filler feed of the cigar machine.

A further object of the invention is to provide an improved method of forming blended cigar bunches.

Another object of the invention is to provide a cigar machine with a cross-feed wherein two different types of filler tobacco may be blended into a composite stream or layer from which filler sections may be separated for the formation of a blended cigar bunch.

2

Another object of the invention is to provide a cross-feed construction having a filler feed channel provided with compartments in which the filler tobacco may be properly blended and fed.

Still another object is to provide an upwardly flared construction of the compartments of the filler feeding channel permitting the manual insertion of the filler tobacco. For this purpose the side belts of the filler feed channel may have outwardly inclined portions. The side belts of the filler feed channel also have portions which converge toward each other while advancing the separate streams of the filler tobacco along the compartments. Thus the tobacco will be redistributed to obtain a more uniform thickness thereof.

When the streams of filler tobacco are advanced beyond the partition, they will then merge with one another to form a composite stream of blended filler tobacco from which bunch lengths are separated. These bunch lengths will be assembled to form a column of tobacco from which bunches are separated for the formation of cigar bunches.

With these and other objects not specifically mentioned in view, the invention consists in certain constructions and methods which will be hereinafter fully described and set forth in the appended claims.

30 In the accompanying drawings which form a part of this specification:

Fig. 1 is a plan view taken from line 1—1 of Fig. 2 of a cigar bunch making machine equipped with a cross-feed blending device embodying my invention;

Fig. 2 is a sectional side elevation of the same taken along line 2—2 of Fig. 1;

Fig. 3 is a cross-section of the filler feed channel, taken on line 3—3 of Fig. 1, showing the inclined portions of the side feed belts thereof;

Fig. 4 is a similar cross-section of a modified cross-feed channel having a portion of one side feed belt outwardly inclined and the other side feed belt in a vertical plane;

Fig. 5 is a sectional end elevation showing the filler column in the measuring chamber, cutting of a bunch charge from the bottom of the tobacco column in the measuring chamber and the transfer of the bunch charge on to the rolling apron of the cigar bunch making machine;

Fig. 6 is a sectional detail view of the rider plate in its operative position wherein it holds down the bunch charge upon the rolling apron while the charge is being coiled upon itself; and

Fig. 7 is a sectional view of a blended cigar bunch obtained with my cross-feed blending de-

vice, showing the blending tobacco in the center of the bunch.

Referring to Figs. 1 and 2 of the drawings, it will be seen that the filler feeding channel of the cross-feed is provided with a longitudinal partition 10 serving to divide the channel into two compartments into which two different types of filler tobacco may be manually inserted to form two streams of filler tobacco. The feeding channel is formed by a horizontal feed belt 12 and spaced side belts 14 and 16 which are mounted on pulleys or rollers intermittently driven by suitable means (not shown) such as illustrated in Wheeler Patent No. 2,311,011, or the copending application of J. P. Durning, S. N. 522,701, filed February 17, 1944. The belt 12 runs over a pulley 18 mounted on a shaft 20 supported in a bracket 22 of the machine and over a pulley 24 also supported by the machine. The side belts 14 and 16 are driven by the rollers 26 and 28, respectively. Rollers 26 and 28 are mounted on vertical shafts 30 and 32, respectively. Belts 14 and 16 also run over idler rollers 34 and 36, respectively, mounted on vertical studs 38 and 40 extending upwardly from bracket 22. Shafts 30 and 32 and the shaft of pulley 24 are intermittently driven from mechanism such as shown in the above mentioned Wheeler patent or Durning application to advance the streams of filler tobacco H and R formed in the compartments of the filler feed channel and thereby form a composite stream of filler tobacco in a manner which will be hereinafter more fully described.

The inner runs of belts 14 and 16 are outwardly inclined at the portions 42 and 44 thereof in order to provide sufficient space through which the operator can insert the long filler leaf tobacco into the filler feeding channel at each side of the partition 10. Said partition permits the operator to place a quantity of the main leaf tobacco into the larger compartment 46 and blending tobacco such as Havana long filler leaf tobacco into the smaller compartment 48. In this manner layers or streams of filler tobacco H and R are formed in the compartments of the filler feed channel.

Both of the inner runs of the belts 14 and 16 should have outwardly inclined portions opposite the partition 10 when a narrow filler feed channel of approximately 1 1/8" width is used to provide upwardly flared compartments into which the filler tobacco is inserted. If a filler feed channel of a standard width of approximately 2 1/4" is used only the vertical run engaging the stream of blending tobacco needs to be outwardly inclined. It will be recalled that the width of the compartment into which the blending tobacco is inserted may be only a minor fraction of the width of the filler feed channel, because the proportion of the blending tobacco may vary from 10% to 25%. Therefore it would be difficult to insert blending tobacco into the narrow width of this compartment on either a standard or narrow filler feed channel unless the adjoining section of the side belt is outwardly inclined. This is particularly true when the width of the blending compartment may be only 10% of the width of the filler feed channel. However with a standard width filler feed channel only the vertical run engaging the blending tobacco needs to be outwardly inclined.

One end of the partition 10 is carried by a block 50 adjustably mounted on a stud 52 which is supported between guide brackets 54 and secured in place by screws 56. The block 50 is retained in position on stud 52 by a clamp screw 58. The

opposite end of partition 10 is connected to a block 60 adjustably secured to a plate 62 having horizontally extending ears 64 which are suitably attached to a supporting plate 66 fastened to the bracket 22. The plate 66 has an opening through which the belt 12 extends and a portion which underlies the upper run or loop of the belt 12, thus supporting the upper run of said belt. The block 60 is secured in position by a screw 68 passing through an elongated slot 70 provided in the plate 62. Upon loosening screws 58 and 68 the partition 10 may be moved laterally to alter the size of compartments 46 and 48 and thus change the proportions of the filler tobacco being blended in the filler feed channel.

The member 10 may also be adjusted vertically to alter the space between the belt 12 and the bottom edge of partition 10. This adjustment is provided to permit the bottom portion of the filler tobacco inserted into compartments 46 and 48 to intermingle to form a solid stream. If the streams of tobacco were not permitted to intermingle under the partition 10 they would not be properly fed, because the friction of the belts 14 and 16 on the outer sides of the streams might not be sufficient to overcome the friction of the partition 10 on the inner sides of the streams. To permit vertical adjustment for obtaining the proper spacing thereof from belt 12, member 10 is provided with a vertically extending ear 72 having an elongated slot 74 in which engages a clamp screw 76. The opposite end of partition 10 has a similar vertically extending ear 78 which is provided with an elongated slot 80 engaged by a clamp screw 82. The blocks 50 and 60 have open end slots 84 and 86 respectively, adapted to receive the ends of member 10 and permit the same to be vertically adjusted upon loosening screws 76 and 82.

The portions 42 and 44 of both side feed belts 40 may be maintained in outwardly inclined positions by members 88 mounted on the table 66 (Figs. 3 and 4). Members 88 span the space between the rollers of each side belt and are provided on their inner faces with inclined portions 45 which maintain portions of the inner runs of each belt 14 and 16 in inclined positions. The side belts 14 and 16 are also guided by lips 90 and 92 depending from their respective guard shells 94 and 96 which are secured to members 88 and 50 cover the top and outer runs of belts 14 and 16. When the belts 12, 14 and 16 are intermittently advanced the streams of tobacco H and R are compressed against partition 10 as they encounter the converging portions 98 and 100 of the side belts 55 whereby the tobacco in streams H and R will be redistributed to obtain a more uniform thickness thereof.

At the lower end of a vertically slidable member 60 102 is fastened a horizontal compressor foot 104 extending along the delivery end of the filler feeding channel. To foot 104 is secured a vertical guide stud 106 slidably mounted in a hub 108 of a standard 110 which forms part of the 65 cigar machine. The compressor foot 104 supports a hinged extension plate 112 which is connected by a link 114 to a pressure arm 116 pivoted to a stud 118 supported by suitable lugs 120 projecting from standard 110. Plate 112 is actuated 70 and controlled by a member 122 whose lower end is pivoted to a bracket 124 secured to compressor foot 104. The upper portion of member 122 protrudes through the pressure arm 116 and has threaded thereon a washer 126 engaging the bottom of arm 116. Member 122 is also provided

with a loose top washer 128 which is held in contact with arm 116 by a tension spring 130 whose pressure is readily adjustable by a pair of lock nuts 132 threaded on member 122. Since the mechanism for vertically reciprocating the member 102 is fully disclosed in the above mentioned Durning application, further description thereof is deemed unnecessary.

The compressor foot 104 and its extension plate 112 serve to compress the tobacco streams H and R after they are advanced out of compartments 46 and 48 and thereby commingle the same to form a composite or blended stream of filler tobacco F. When the corrugated cutter 134 is moved downward by a slide 136 actuated by mechanism described in the above mentioned Durning application, in the direction of the arrow in Fig. 2, compressor foot 104 also moves downward and the composite tobacco stream F formed underneath said compressor foot and its hinged extension is firmly held in position during the cutting of a bunch length by corrugated cutter 134. The compressor foot and its extension plate 112 are at least twice as long as the length of the filler section severed from the composite filler stream F so that when the leading end of the filler stream F is advanced into the extension channel formed by side guides 138 to be cut off by the cutter 134 it will be compressed twice. Therefore the flat and even layers of tobacco in the leading end of the filler stream F are not likely to be disturbed when moved on to a charge supporting plate 140 which forms the bottom of the extension channel. The cutting of the bunch length section from the filler stream F is effected by the coaction of corrugated cutter 134 with a stationary ledger plate 142 forming a bridge between the horizontal feed belt 12 and the horizontal charge supporting plate 140. Ledger plate 142 is mounted on a bridge bracket 144 attached to the end of a cross-feed supporting member 146 whose construction is fully described in the above mentioned Durning application. In order to assure that all filler tobacco placed by the operator into the filler feeding channel is properly guided underneath the compressor foot 104 and its hinged extension 112, a pair of guide brackets 54, which are secured to the top of guard shells 94 and 96, form together with said hinged extension 112 when the latter is in its upper position a funnel which smoothly directs any projecting piece of the advancing tobacco stream underneath the compressor foot 104 without causing obstructions or clogging.

When the corrugated cutter 134 descends during its cutting action, the charge supporting plate 140 is quickly withdrawn. The bunch length C severed from the filler stream F drops into a stationary measuring chamber M consisting of a pair of side walls 148 and 150, corrugated end wall 152, and a straight end wall 154. The latter by means of a lug 156 is mounted on a stationary bearing bracket 158 fastened to a slide supporting bracket 160 attached to the bed 161 of the machine. The corrugations in the inner face of end wall 152 correspond with the corrugations of the cutter plate 142 and serve to maintain alignment of the superimposed ends of the bunch lengths and prevent their disturbance while being deposited into measuring chamber M. The charge supporting plate 140 is slidably supported in a space provided between the top of the measuring chamber M and the guide plates 138 and also the ledger plate 142. The hori-

zontal charge supporting plate is intermittently reciprocated by means of an arm 162 which, through a link 164 is connected to a lug 166 attached to the plate 140. A stationary guide rod 168 held by a suitable hub on side wall 150 of measuring chamber M projects from the same and slidably engages with a suitable hole in the lower portion of lug 166, thus guiding the reciprocating charge supporting plate 140. The arm 162 is suitably actuated by means (not shown) corresponding to mechanism disclosed in the above mentioned application of J. P. Durning.

Underneath the measuring chamber M is located a slidably mounted charge transfer T (Figs. 1, 2 and 5) provided with two side walls 170 and one end wall 172. The other end wall is formed by a lug 174 to which side walls 170 are fastened. The lug 174 projects from a sleeve 176 slidably supported by a horizontal shaft 178 held by the bracket 158. At the other end of the charge transfer T the wall 172 is guided and supported in the same manner disclosed in the above mentioned application of J. P. Durning. The lower portion of sleeve 176 (Fig. 2) is equipped with a lug 180 having a stud 182 supporting one end of a link 184 (Fig. 2) connected to suitable actuating means shown in the above mentioned Durning application.

Operating in synchronism with the corrugated cutter 134 is a measuring plunger 186 which trails slightly behind said cutter until the latter has severed the bunch length C from the filler stream F (Fig. 2). The cutter then stops and remains stationary while the measuring plunger continues descending to compress the severed bunch length on to the tobacco column D which constitutes an accumulation of several bunch lengths. When the corrugated cutter 134 and measuring plunger 186 start descending a measuring platform 188 which closes the bottom opening of the charge transfer T (Figs. 2 and 5), ascends into the charge transfer and moves the tobacco column D which rests on the platform 188 slightly upward. As mentioned heretofore, the charge C cut from the filler stream F drops on top of said column D with the plunger 186 following said charge. When the measuring plunger engages said tobacco column, the measuring platform 188 is in its uppermost position and inside of the charge transfer. The measuring plunger 186 continues its downward movement for a short distance to effect compression of the tobacco column D in measuring chamber M and the charge transfer T.

After the measuring plunger has come to rest with the compacted column D between the plunger 186 and the measuring platform 188, a straight knife or cutting plate 190 horizontally enters the space 192 (Fig. 5) provided between the bottom of the measuring chamber and the top of the charge transfer and thereby separates a bunch charge B from the compacted tobacco column D. The height or thickness of the charge is determined by the distance or space between the measuring platform 188 and the knife 190. Therefore, the setting of this distance is made to correspond with the desired thickness of the charge. After cutting of said charge B from the tobacco column D the measuring platform 188 descends and stops in a position which is below the bottom of the charge transfer T and aligned with a stationary bridge plate 194. The charge B is then moved by said transfer in the direction of the arrow in Fig. 5, over the stationary

bridge plate 194 and over a rider plate 196 on to the rolling apron 198 of the bunch rolling mechanism of the cigar machine.

The construction of the bunch rolling mechanism is similar to that shown in the above mentioned Durning application and the co-pending application of R. E. Rundell, S. N. 589,514 filed April 21, 1945, although the type of bunch rolling mechanism shown in the Wheeler Patent 2,311,011 may be used. Charge B is ejected from the charge transfer T by an ejector 200 (Figs. 1 and 5) which together with a platform 202 supporting apron 198, guides said charge out of the charge transfer T and lowers the same upon apron 198 to a position in line with the rolling table 204 of the bunch rolling mechanism of the machine. Since the construction of the bridge plate 194, apron 198, ejector 200, and platform 202 is fully described in the said Durning and Rundell applications, further description thereof is deemed unnecessary. A loop or pocket former 206 connected to and movable with the ejecting plunger 200 is employed for the purpose of positioning and laying the apron flat and even over the platform 202 when reaching its lowermost position, as shown in dotted lines in Fig. 5. The ejecting plunger 200 and loop former 206 then ascend again and rolling pin 208 advances in the direction of the arrow (Fig. 6) and rolls the charge to form a cigar bunch in a manner hereinafter described. As soon as plunger 200 and loop former 206 have reached their uppermost position the charge transfer T moves back to its original position in alignment with measuring chamber M, whereupon the knife 190 withdraws and the remaining portion of the tobacco column in measuring chamber M drops into the charge transfer. While the charge transfer T was moving charge B on to the rolling apron 198, the charge supporting plate 140 moved in again, covering the measuring chamber M ready to support the advancing end of the tobacco filler stream F from which another bunch length is to be cut. After withdrawal of plate 140 this bunch length is also deposited on to the top of the tobacco column D in the measuring chamber M and transfer T.

The free end of the compressor foot 104 is provided with corrugations 210 which interengage corrugations of the cutter 134 and thereby assure that the filler stream F will be compressed and held down adjacent cutter 134. The corrugations 210 of foot 104 also act as a scraper for any particles of tobacco which might cling to the ascending cutter 134. One end of the measuring plunger 186 is also provided with corrugations which correspond to the corrugations of cutter 134 and fit into the contour of the corrugated end wall 152 of measuring chamber M, thus providing means for a firm lateral compaction, not only of the center portion of the tobacco column D but of its corrugated ends as well. The measuring plunger is attached to the lower end of a vertical shaft 212 (Figs. 2 and 5) slidably supported by means of a bearing bracket 214 attached to standard 110. The upper end of shaft 212 is supported in the same manner as disclosed in the Durning application previously mentioned and operated by mechanism described therein so a detailed description is believed unnecessary. To prevent turning of the measuring plunger 186, the latter is provided with a vertical guide rod 216 projecting from said plunger and engaging with a guide sleeve 218 extending from bracket 214.

The measuring platform 188, which controls the thickness of the charge B cut by the horizontal knife 190 from the bottom of the tobacco column, is mounted on a vertical shaft 220 slidably supported in a bearing bracket 222 which is attached to a bracket of the machine, not shown. The downward movement of the measuring platform 188 is arrested by a pair of stop screws 224 contacting the lower side of said measuring platform and assuring a correct alignment of the same with the stationary bridge plate 194. Stop screws 224 are carried by a pair of lugs 226 projecting from bracket 222. A complete description of the mechanism for operating platform 188 will be found in the above mentioned Durning application.

The straight knife 190, which cuts the charge B from the tobacco column D, is adjustably mounted on a horizontal slide 228 supported and guided by a dove tailed channel 230 in the upper portion of the slide supporting bracket 160. The operation of the slide 228 and the knife 190 is accomplished by mechanism described in the Durning application previously mentioned. Therefore a detailed description of the same is omitted in the interest of brevity.

When the charge transfer is returned to its position underneath the measuring chamber after delivering the blended charge B on the rolling apron 198, rider plate 196 is turned 180° to engage the top of the charge B. For this purpose plate 196 is mounted on a pair of lugs 860 secured to a shaft 862 mounted in bearings in the arms of a horizontally reciprocable U-shaped bracket 864. Since the parts 860, 862 and 864 correspond to similarly numbered parts in the above-mentioned Rundell application, further description thereof is deemed unnecessary. The rolling pin 208, which is mounted on shaft 862, is then moved in the direction of the arrow (Fig. 6) and starts to coil the charge upon itself. The shaft 862 is turned to lay the plate 196 against the top of the charge by mechanism similar to that described in said Rundell application. The bracket 864 in being advanced also advances the rolling pin 208 and rider plate 196, and the flat charge B is rolled up from its rear edge at which the blending tobacco is located, somewhat as a carpet is rolled up. As the coiled bunch continues moving over the surface of the rolling apron it is rolled up in a binder W which has been placed previously on the apron. When the binder W is wound about said charge there is formed a cigar bunch N such as shown in Fig. 7. The Havana filler or other blending tobacco H placed in the compartment 48 of the cross-feed channel, when arriving on the rolling apron 198, is at the rear edge of the charge; and therefore, when said charge is rolled, it will be placed in the center of the cigar bunch N. The finished bunch therefore will consist of a core H of Havana filler or other blending tobacco surrounded by the body filler tobacco R as shown in Fig. 7.

A modified form of the cross-feed channel is shown in Fig. 4, in which the inner run of the side belt 14 of the narrow blending compartment has a portion arranged in an inclined plane to permit insertion of the Havana or other blending filler tobacco H. The larger compartment has the entire inner run of its side belt 16 in a vertical plane. This construction can be used for the latter compartment with a standard width or wider filler feed channel, since there will then be enough room for the operator

to place the regular or body filler tobacco R into this compartment. The guard shell 95 which encloses the top and outer run of the belt 16 is made in the conventional manner, and the guard shell 94 is similar to the guard shell 94 shown in Fig. 3.

If desired the partition 10 may be omitted and the body and blending tobacco manually positioned along the inclined portions 42 and 44 of the side feed belts to form a composite stream of filler tobacco. However a less uniform distribution of the blending tobacco in the bunch charges will be obtained in this manner.

While the blending tobacco is preferably located along the longitudinal edge of the bunch charge from which its coiling is begun, to locate it in the interior of the coiled bunch charge, it may be located at any desired position in the cigar bunch by positioning the blending tobacco at various locations along the width of the bunch charge. For example, the blending tobacco may be at the exterior edge of the coiled bunch charge. To produce the latter type of bunch charge the positions of the blending and body filler tobacco compartments of the filler feed channel may be reversed to thereby locate the blending tobacco at the exterior longitudinal edge of the coiled bunch charge. Although I have described my invention in detail and therefore utilized certain specific terms and language herein, it is to be understood that the present disclosure is illustrative, rather than restrictive, and that changes and modifications may be resorted to without departing from the spirit or the scope of the claims appended hereto.

What is claimed is:

1. The combination with mechanism for forwarding a plurality of substantially horizontal streams of different types of tobacco, said mechanism including parallel and mechanically separated channels having a common movable bottom, of means for severing lengths of tobacco from the leading ends of said streams and assembling them to form a composite column having one type of tobacco extending from top end to bottom end along one side of the column and another type of tobacco extending from top end to bottom end along the other side of the column, and means for separating bunch charges from one of said ends of said column to provide a bunch charge containing measured amounts of each of said tobaccos.

2. In a cross feed for cigar bunch machines, the combination with a horizontal bottom belt and opposed side belts arranged to form a traveling channel for forwarding filler tobacco, of a longitudinal partition running lengthwise of said channel along a portion thereof whereby different types of tobaccos may be inserted between said partition and said side belts to form a plurality of continuous streams of different types of tobacco which will be commingled in the portion of said channel beyond said partition, and devices for severing bunch length portions from the composite stream formed by commingling the streams of different tobacco positioned in said channel between said partition and each of said side belts and assembling a plurality of severed bunch length portions to form a composite column from said different tobaccos wherein a plurality of sub-columns each formed of different tobacco extend from one end to the other end of said composite column, and a device for separating a bunch charge from one end of said column.

3. In a cigar machine, the combination with a filler feed adapted to advance a continuous stream of long filler body tobacco and a continuous stream of long filler blending tobacco, whose breadth is less than the breadth of the stream of body tobacco, and commingle said streams to form a composite stream of filler tobacco with the blending tobacco extending along one edge of said composite stream, a conveyor having a horizontal movable bottom with a partition to define channels in which both of said streams move with their inner lateral edges adjacent each other to be commingled with each other, and said conveyor being adapted to advance said composite stream, of mechanism for separating bunch length from the composite stream in side by side relationship, means for assembling the separated bunch lengths to form a column of tobacco having sections of body tobacco and blending tobacco extending from one end thereof to the other end thereof, and a device for separating a bunch charge from one end of said column containing long filler and blending tobacco.

4. A cigar machine filler feed comprising an endless traveling belt having a horizontal run adapted to support filler tobacco, a pair of endless traveling belts having operating runs extending along the edges of said horizontal run and defining a filler feed channel, a stationary partition extending along a portion of said filler feed channel to provide a pair of compartments wherein one type of filler tobacco and a blending tobacco may be respectively inserted to form separate continuous streams of filler tobacco on said horizontal run, members arranged to deflect into converging relationship the portions of said operating runs adjacent the ends of said compartments from which said streams emerge to produce a more uniform distribution of the tobacco in said streams before they are commingled in said channel to form a composite stream, and a compactor for compressing said streams vertically after they emerge from said compartments to commingle the same into a composite stream.

5. A cigar machine filler feed comprising an endless traveling belt having a horizontal run adapted to support filler tobacco, a pair of endless traveling belts having operating runs extending along the edges of said horizontal run and defining a filler feed channel, a thin partition having substantially vertical sides and extending along a portion of said filler feed channel intermediate said operating runs to provide a pair of compartments wherein one type of filler tobacco and a blending tobacco may be respectively inserted to form separate continuous streams of filler tobacco on said horizontal run, the lower edge of said partition being sufficiently spaced from said horizontal run to permit said streams to merge with one another underneath said partition while being advanced on said horizontal run.

6. A cigar machine filler feed comprising an endless traveling belt having a horizontal run adapted to support filler tobacco, a pair of endless traveling belts having operating runs with portions in inclined planes extending along the edges of said horizontal run and defining a filler feed channel, a partition extending along a portion of said filler feed channel to provide a pair of compartments wherein one type of filler tobacco and a blending tobacco may be respectively inserted to form separate continuous streams of

11

filler tobacco on said horizontal run, and members having inclined faces adapted to engage and maintain said portions of said operating runs opposite said partition in outwardly inclined positions to facilitate the insertion of filler tobacco into said compartments.

7. A cigar machine filler feed comprising an endless traveling belt having a horizontal run adapted to support filler tobacco, a pair of endless traveling belts having operating runs, a portion of which is in an inclined plane, extending along the edges of said horizontal run and defining a filler feed channel, a partition extending along a portion of said filler feed channel to provide a pair of compartments wherein one type of filler tobacco and a blending tobacco may be respectively inserted to form separate continuous streams of filler tobacco on said horizontal run, and a member having an inclined face adapted to engage and maintain said portion of one of said operating runs, which is opposite said partition, in an outwardly inclined position to facilitate the insertion of filler tobacco into the adjoining compartment.

8. A process of making cigar bunch charges comprising forming and feeding a continuous stream of long filler tobacco, forming and feeding a narrower continuous stream of blending filler tobacco along one longitudinal edge of the broader filler tobacco stream to merge said streams in a composite filler tobacco stream wherein the blending tobacco extends along one longitudinal edge of the composite stream, separating bunch lengths from said composite stream and assembling the separated bunch lengths to form a column of tobacco, and separating from said column bunch charges containing long filler tobacco and blending tobacco.

9. A process of making cigar bunch charges comprising forming and feeding a continuous stream of body filler tobacco, forming and feeding a continuous stream of blending tobacco, whose breadth is less than the breadth of said stream of body tobacco, along one side of the filler tobacco stream to merge said streams in a composite filler tobacco stream wherein blending tobacco extends along one side of the composite stream, separating bunch lengths from said composite stream and assembling the separated bunch lengths one on top of the other to form a column of tobacco having an uninterrupted sub-column of blend tobacco extending from top to bottom of said column, and separating along a horizontal plane transverse to said sub-column, composite bunch charges containing body filler tobacco and blending tobacco.

10. A cigar machine filler feed comprising an endless traveling belt having a horizontal run adapted to support filler tobacco, a pair of endless traveling belts having operating runs extending along the edges of said horizontal run and defining a filler feed channel, members arranged to deflect portions of said operating runs into positions inclined to the vertical and then into converging relationship whereby body filler tobacco and blending tobacco manually placed upon said horizontal run along said inclined belt portions respectively to form separate continuous streams of body and blending tobacco will be commingled to form a composite stream of filler tobacco, means for separating bunch lengths from said composite stream whereby each separated bunch will have a section of blending tobacco extending through the entire depth thereof along one lateral edge thereof, a device for su-

12

perimposing the bunch lengths to form a vertical column of tobacco wherein the blending tobacco forms an uninterrupted sub-column extending from the upper to the lower end of said column, and mechanism for separating along a horizontal plane transverse to said column composite bunch charges containing body filler tobacco and blending tobacco.

11. In a cross feed for cigar bunch machines, the combination with a horizontal bottom belt, and opposed side belts arranged to form a traveling channel for forwarding filler tobacco through one end of said channel, of a longitudinal partition running lengthwise of the section of said channel adjoining the other end thereof, said opposed side belts having the sections of their operating runs adjoining the delivery end of said channel in upright planes and the sections thereof adjacent said partition in planes inclined upwardly and outwardly to provide an upwardly flared channel section between said inclined belt sections and said partition.

12. A cigar machine filler feed comprising an endless traveling belt having a horizontal run adapted to support filler tobacco, a pair of endless traveling belts having operating runs extending along the edges of said horizontal run and defining a filler feed channel, a thin partition having a substantially uniform thickness and extending along a portion of said filler feed channel intermediate said operating runs to provide a pair of compartments wherein one type of filler tobacco and a blending tobacco may be respectively inserted to form separate continuous streams of filler tobacco on said horizontal run, the lower edge of said partition being sufficiently spaced from said horizontal run to permit said streams to merge with one another underneath said partition while being advanced on said horizontal run, and means for adjustably mounting said partition for movement toward and away from said horizontal run.

13. A process of making cigar bunches comprising forming and feeding a relatively broad stream of filler tobacco, forming and feeding a narrower continuous stream of blending filler tobacco along one longitudinal edge of the broader filler tobacco stream to merge said streams in a composite filler tobacco stream wherein the blending tobacco extends along one longitudinal edge of the composite stream, separating bunch lengths from said composite stream and superimposing the bunch lengths to form a vertical tobacco column, compacting said column and separating from one end thereof of a bunch charge having the blending tobacco extending along one longitudinal edge thereof, coiling the bunch charge upon itself with the blending tobacco located inside the coiled bunch charge, and wrapping the coiled bunch charge within a wrapper to form a cigar bunch.

14. The combination with mechanism for forwarding a plurality of substantially horizontal streams of different types of tobacco, said mechanism including parallel and mechanically separated channels having a common movable bottom, said channels including superposed laterally spaced sides independent of the bottom, of means for severing lengths of tobacco from the leading ends of said streams and assembling them to form a composite column having one type of tobacco extending from top end to bottom end along one side of the column and another type of tobacco extending from top end to bottom end along the other side of the col-

umn, and means for separating bunch charges from one of said ends of said column to provide a bunch charge containing measured amounts of each of said tobaccos.

15. The combination with mechanism for forwarding a plurality of substantially horizontal streams of different types of tobacco, said mechanism including parallel and mechanically separated channels having a common movable bottom, said channels including superposed laterally spaced inclined sides independent of the bottom, of means for severing lengths of tobacco from the leading ends of said streams and assembling them to form a composite column having one type of tobacco extending from top end to bottom end along one side of the column and another type of tobacco extending from top end to bottom end along the other side of the column, and means for separating bunch charges from one of said ends of said column to provide a bunch charge containing measured amounts of each of said tobaccos.

16. The combination with mechanism for forwarding a plurality of substantially horizontal streams of different types of tobacco, said mechanism including parallel and mechanically separated channels having a common movable bottom, said channels including superposed laterally spaced sides independent of the bottom, of means for severing lengths of tobacco from the leading ends of said streams and assembling them to form a composite column having one type of tobacco extending from top end to bottom end along one side of the column and another type of tobacco extending from top end to bottom end along the other side of the column, means for separating bunch charges from one of said ends of said column to provide a bunch charge containing measured amounts of each of said tobaccos, and means closely adjacent the separating means for coiling the bunch charge upon itself while simultaneously locating the blending tobacco entirely interiorly of the bunch charge.

17. The combination with mechanism for forwarding a plurality of substantially horizontal streams of different types of tobacco, said mechanism including parallel and mechanically separated channels having a common movable bottom, said channels including superposed laterally spaced inclined sides independent of the bottom, of means for severing lengths of tobacco from the leading ends of said streams and assembling them to form a composite column having one type of tobacco extending from top end to bottom end

along one side of the column and another type of tobacco extending from top end to bottom end along the other side of the column, means for separating bunch charges from one of said ends of said column to provide a bunch charge containing measured amounts of each of said tobaccos, and means closely adjacent the separating means for coiling the bunch charge upon itself while simultaneously locating the blending tobacco entirely interiorly of the bunch charge.

18. The combination with mechanism for forwarding a plurality of substantially horizontal streams of different types of tobacco, said mechanism including parallel and mechanically separated channels having at least one common wall therebetween, said channels having movable bottom portions and contiguous sides above the bottom portions, of means for severing lengths of tobacco from the leading ends of said streams and assembling them to form a composite column having one type of tobacco extending from top end to bottom end along one side of the column and another type of tobacco extending from top end to bottom end along the other side of the column, and means for separating bunch charges from one of said ends of said column to provide a bunch charge containing measured amounts of each of said tobaccos.

PONTUS PETERSON.
